UNITED STATES PATENT OFFICE.

JOHN P. NELSON, OF WALTHAM, MASSACHUSETTS.

TENT.

SPECIFICATION forming part of Letters Patent No. 707,347, dated August 19, 1902.

Application filed December 5, 1901. Serial No. 84,786. (No model.)

To all whom it may concern:

Be it known that I, JOHN P. NELSON, a citizen of the United States, residing at Waltham, in the county of Middlesex and State of Massachusetts, have invented certain new and useful Improvements in Tents; and I do hereby declare the following to be a full, clear, and exact description of the invention, such as will enable others skilled in the art to which it appertains to make and use the same.

This invention relates to portable buildings or tents; and it consists in the novel construction and combination of the parts hereinafter fully described and claimed.

15 In the drawings, Figure 1 is a front view of the tent, partly in vertical section. Fig. 2 is a sectional plan view.

The bottom or floor A of the tent is composed of two sections, which are provided 20 with hinges a', so that they may be folded one onto the other when the tent is taken apart.

The tent is provided with a knockdown frame comprising uprights B, top cross-pieces 25 b, and inclined rafters b'. The rafters b' are connected to the angles of the frame and meet together over the center of the frame. The frame and the floor are joined together by bolts or any approved fastening devices, so 30 that they can be quickly taken apart. The frame is also provided with a hinged door C, which preferably opens inward.

The roof of the tent is formed of an outer cover D, of textile material, such as canvas, 35 which rests upon the rafters and is provided with a flounce d at its lower edge, which overlaps the top cross-pieces b.

The sides of the tent consist of a broad band E, of textile material, which is attached 40 to the outside of the frame by any approved fastening devices, such as the spring-caps commonly in use. The band E extends all around the frame except the door, and its lower edge has a flounce e for carrying the 45 fastening devices. The upper edge of the band is secured to the underside of the flounce

d of the roof by approved fastening devices, such as hooks and eyes e'.

The tent is provided with a lining F, of textile material, such as canvas. This lining extends under the roof and around the walls, and f are air-spaces between the lining and the roof and the outer sides E of the tent. The lining F of the tent is attached to the inside of the frame by any approved fastening 55 devices. The lining is provided with window-openings h, and the sides are provided with window-openings i. These openings are arranged opposite each other and are provided, respectively, with flaps h' and i', which may 60 be rolled up independently and secured by straps to afford a free passage for light and air in fine weather. These curtains when closed are secured by any approved fastening devices. 65

The whole tent is arranged so that it may be quickly put together and taken apart, and the air-spaces prevent the cold and wet from penetrating into its interior.

What I claim is—

In a tent, the combination, with a knockdown frame, of an outer covering of textile material extending over the exterior of the top and sides of the frame and provided with window-openings, an inner covering of textile material extending over the interior of the top and sides of the frame and provided with window-openings opposite the aforesaid window-openings, air-spaces being formed of the width of the elements of the said frame 75 between the two said coverings, and curtains of textile material for closing the said window-openings arranged inside the inner covering and outside the outer covering respectively, substantially as set forth. 80

In testimony whereof I affix my signature in presence of two witnesses.

JOHN P. NELSON.
